UNITED STATES PATENT OFFICE.

EDWARD W. PELZER, OF CHICAGO, ILLINOIS, ASSIGNOR OF ONE-HALF TO BRUNO R. BELZ, OF CHICAGO, ILLINOIS.

DISPLAY CABINET.

Application filed March 26, 1923. Serial No. 627,791.

To all whom it may concern:

Be it known that I, EDWARD W. PELZER, a citizen of the United States, and a resident of the city of Chicago, in the county 5 of Cook and State of Illinois, have invented certain new and useful Improvements in a Display Cabinet; and I do hereby declare that the following is a full, clear, and exact description of the same, reference 10 being had to the accompanying drawings, and to the numerals of reference marked thereon, which form a part of this specification.

This invention relates to a display cabinet 15 or case for neck ties or the like.

It is an object of this invention to provide a cabinet having a novel form of tie suspending rack hinged therein and provided with means for controlling the same 20 during the outward swinging movements thereof and for retaining the same in different positions.

With these and other objects in view, which will become more apparent in the following description and disclosures in the drawings, this invention comprises the novel mechanism and combinations hereinafter described and more particularly pointed out and defined in the appended claims.

30 In the accompanying drawings, which illustrate a preferred embodiment of this invention, and in which similar reference numerals refer to similar features in the different views:

35 Figure 1 is a front elevational view of the cabinet showing the tie supporting rack in its housed position.

Figure 2 is an enlarged and broken sectional view of a tie supporting rack.

40 Figure 3 is an enlarged fragmentary bottom plan view of a tie rack.

Figure 4 is an enlarged sectional view through a guide showing the controlling rod for the racks in elevation.

45 Figure 5 is a section through the cabinet showing the top plan view of the tie supporting racks.

Figure 6 is an enlarged side elevational view of a tie rack.

50 Figure 7 is an enlarged fragmentary elevational view of the rack support and the locking latch.

Figure 8 is a diagrammatic view illustrating the tie supporting racks in an outwardly swung position.

Figure 9 is a section through a tie supporting rack illustrating the manner of supporting a tie.

As shown on the drawings:

In referring now to the drawing, there is illustrated a cabinet 1 which may be constructed of any suitable material such as wood or metal. While the cabinet may be of any particular shape or design, a substantially cubical one has been illustrated. 60

A hinged member 2 which serves as a support for tie supporting racks is hinged at its forward end to the inner front and upper margin of one of the lateral sides of the cabinet, as indicated at 3 (Fig. 1). This hinge member 2 is a trifle shorter than the lateral sides of the cabinet so that it may readily be swung inwardly and outwardly, and it is preferably of a depth corresponding to the depth of the racks. 70

Upon the lower rear side of the hinged member 2, there is a slidably latch 4 (Fig. 7) supported in suitable bearings 5 and 6 and provided with a downwardly projecting handle 7 for operating the same. The rear end of the latch is adapted for co-operation with a keeper 8 (Fig. 5) upon the rear wall of the cabinet for retaining the hinged rack supporting member 2 in proper position within the cabinet, as shown in Figs. 1 and 5. 80 A second keeper 9 is secured upon the front lateral side of the cabinet opposite the hinges 3 into which the latch bar is adapted to be snapped when the hinged member is swung outwardly, as shown in Fig. 8, for retaining 90 the same in such position.

Hinge members 10 and 11, preferably in the form of metal plates, are secured to the upper and lower margins of the hinged member 2, the upper member 11 being provided with a hollow guideway at its upper end for housing the control rod 12 shown in Fig. 4. At suitably spaced intervals these hinge members 10 and 11 are provided with hinge eyes 13 over which the hinge ears 14 of the tie racks fit; pivot pins extending through said eyes and ears for hinging the tie racks to the hinge members. 100

In the present embodiment of this invention, these tie supporting racks comprise an upper rack member 15 hinged to the member 11 and a lower rack member 16 hinged to the member 10, the free ends of the respective rack members of a rack being connected by a vertical tie piece 17. Adjacent the outer 110

ends of the upper rack members 15 are resilient spacing and buffer members 18 which may be struck therefrom, the outside rack members 15 having but one spacing buffer 18 which is positioned upon the inner side thereof, while the intermediate rack members 15 have a spacing buffer upon each side, as shown in Fig. 8. These spacing buffers maintain the different racks in proper spaced relation at their outer ends. Each upper rack member 15 is provided with separate spaced compartments 19 through which a folded tie may pass. In the exemplification of this invention, each upper rack member 15 is formed by folding a thin strip of metal to provide two parallel portions suitably spaced apart, forming the hinge ears at the closed end and securing the free ends to the tie pieces 17. At suitable intervals partitions 20 connect the parallel portions and divide the space therebetween into a number of separate compartments 19 open at the upper and lower ends. These partitions 20 may be in the form of metal pieces having lateral lugs extending through suitable apertures in the parallel portions and crimped thereover.

The lower rack members 16 consist in the present instance each of a folded metal strip having hinge ears 13 formed at its folded end and secured at its free ends to a tie piece 17. Rivets may be used to secure the folded portions in contiguous relation. At suitable intervals, corresponding to the compartments in the upper rack member, tie retainers 21 are provided upon opposite sides of the lower rack member. In the present instance, these tie retainers are in the form of tongues struck from the folded portions and bent in spaced parallel relation therewith so that a folded portion of a tie may be slipped thereon. In suspending a tie 26 upon a rack, the tie is folded longitudinally by superposing one half upon the other half and passing the folded end down through a compartment in the upper rack member and attaching the looped end over a retainer 21. The open compartments 19 are sufficiently wide so that two folded ties may be passed therethrough and their looped ends hung upon opposite retainers 21, as shown in Fig. 8, with the free ends dangling over opposite sides of the upper rack member.

The hinge member 2 with the tie racks hinged thereto is normally positioned within the cabinet, which may be provided with a door 1' for closing the same. When it is desired to exhibit the ties, the door is opened and the racks swung outwardly, as shown in Fig. 8, whereby the ties may be readily inspected by swinging the racks as illustrated, and in which position new ties may be placed thereon.

As the racks extend substantially the lateral width of the cabinet, it is necessary that

they be swung obliquely at angles to the hinged supporting member 2 when they are swung outwardly or inwardly of the cabinet. It is therefore necessary to provide some means to swing the racks obliquely in an outward direction before they can be bodily swung outwardly. For this purpose, the control rod 12 is connected by a flexible connection 22 with the last or innermost rack (Fig. 5), so that when the rod 12 is pulled outwardly it will swing the racks to oblique positions, as shown in dotted lines in Fig. 5, in which positions they will clear the opposite side of the cabinet. In the present instance, the flexible connection 22 consists of a pair of jointed links having the old form of slot and pin, lost motion connection with the innermost rack. The rod 12 is housed in the aforementioned guideway of the upper hinge member 11 and is provided with a collar 23 at its inner end from which a bolt 24 projects through a slot in the guideway for attachment to the flexible connection 22. A coil spring 25 is confined within the guideway and around the rod 12 and abuts the collar 23 and the forward end of the guideway through which the rod 12 projects so that it may be grasped and pulled outwardly.

It will be appreciated that by providing means for first swinging the tie racks obliquely before they are bodily swung from the cabinet or case, it is possible to use a smaller case and one that need not be provided with extra space to allow for the radius of movement. It is also characteristic of this invention that the ties can be readily inspected by swinging the racks, but cannot be easily removed by a purchaser who is often prone to unattach and handle a great many. The construction is also unique in that it will accommodate a complete set of ties of different colors or shades according to the manufacture.

I am aware that numerous details of construction may be varied through a wide range without departing from the principles of this invention, and I therefore do not purpose limiting the patent granted otherwise than necessitated by the prior art.

I claim as my invention:

1. A tie display cabinet comprising a receptacle having a door at its front end, a member hinged to the forward upper inner margin of said receptacle and swingable inwardly and outwardly of said receptacle, tie supporting racks hinged to said member, a latch supported by said member, keepers, one on the rear wall of said receptacle and the other on the forward margin of the lateral wall, for engagement with said latch, and a yieldingly supported pull-rod slidingly mounted on said member and connected to one of said racks for the purpose set forth.

2. In a tie display cabinet, a hinged member pivoted to swing inwardly and outwardly of said cabinet, latch mechanism for retaining the same in different positions, tie racks hinged to said member, and a yieldingly and slidably supported rod connected to the rear rack and operative for swinging the racks on their hinge connections and for swinging said member when in unlatched position.
3. In a tie display cabinet, a hinged member adapted to swing inwardly and outwardly of said cabinet, and tie racks hinged to said member, said racks having end spacing members struck from the body thereof for retaining the same in spaced parallel relation.
4. In a tie display cabinet, a hinged member adapted to be swung inwardly and outwardly of said cabinet, and tie-holding racks hinged to said member, each having a plurality of separate tie-retaining compartments longitudinally disposed therein.
5. In a tie display cabinet, a hinged member adapted to be swung inwardly and outwardly of said cabinet, tie suspending racks hinged to said member, a longitudinally yieldable rod supported by said member, and

a flexible connection between said rod and the rear rack for the purpose set forth. 30

6. In a tie display cabinet, a hinged member adapted to be swung inwardly and outwardly of said cabinet, and tie holding racks hinged to said member, and comprising upper and lower members, the upper members having separate compartments for receiving individual ties and the lower members having retainers for engagement with the ties when looped. 35

7. In a tie display cabinet, a hinged member adapted to be swung inwardly and outwardly of said cabinet, and tie holding racks hinged to said member, and comprising upper and lower members, the upper members having separate compartments for receiving individual ties and the lower members each having retainers upon opposite sides thereof for engagement with separate ties when looped. 40

In testimony whereof I have hereunto 50 subscribed my name in the presence of two subscribing witnesses.

EDWARD W. PELZER.
